UNITED STATES PATENT OFFICE.

CARL MARSCHÜTZ AND HEINRICH MARSCHÜTZ, OF NUREMBERG, GERMANY.

SPANNER.

SPECIFICATION forming part of Letters Patent No. 635,562, dated October 24, 1899.

Application filed March 21, 1899. Serial No. 709,996. (No model.)

To all whom it may concern:

Be it known that we, CARL MARSCHÜTZ and HEINRICH MARSCHÜTZ, subjects of the King of Bavaria, residing at Nuremberg, in the 5 Kingdom of Bavaria and German Empire, have invented certain new and useful improvements in spanners for machines and devices of all kinds, particularly applicable for cycles and automotors, (for which we have 10 applied for a patent in England, dated January 11, 1899, No. 716,) of which the following is a specification.

This invention relates to a new spanner for machines and other devices, is particularly 15 applicable for cycles and automotors, and is adapted to nuts and screw-heads of various sizes without alteration of the mouth of the spanner. Further, the spanner is constructed to fold into a small compass; but when in use 20 it has sufficient mechanical advantage and rigidity to do the work effectively. Therefore it answers especially the requirements for cycles and automotors; but when constructed of suitable proportions it is also use- 25 ful for erecting machinery and in engineering work generally.

In order that this invention may be the better understood, we now proceed to describe the same, reference being had to the accom- 30 panying drawings and to the letters marked thereon.

Figures 1 and 2 are views of the spanner when folded to be put away. Figs. 3 and 4 show different positions of the spanner when 35 in use.

The several arms or members *a*, which may be of any suitable shape and size of jaw or hole, are connected at one extremity, so as to pivot, by a bolt *c* or a rivet-screw or other de- 40 vice and a shoulder-piece *b*. For putting away, the arms or members *a* are folded to-

ward one side, as shown in Figs. 1 and 2. For use the members of the desired size of jaw or hole (*a*' in the drawings) are turned through about one hundred and eighty degrees, as 45 shown in Fig. 3. Thus the spanner has double the leverage of the separate members. The members not used for screwing serve as a convenient handle.

The back of the shoulder-piece *b* is suffi- 50 ciently broad to serve as a counter-support to prevent the folding up of the extended spanner. If desired, the shoulder *d* of the piece *b* may be somewhat elongated and have a slot and a square or other hole to serve as a nozzle- 55 spanner and for similar purpose. Further, the spanner may be provided with a screw-driver *f*, Fig. 4. For use as a screw-driver several members *a* are extended, and the screw-driver *f* is turned so that it forms a 60 right angle to the members *a*, the latter serving as a handle.

What we claim, and desire to secure by Letters Patent of the United States, is—

A spanner comprising a plurality of mem- 65 bers, a bolt pivotally connecting the ends of said members and a clip having laterally-ex- tending ears, said members fitting in between said ears and said bolt extending through the same, the intermediate part of said clip lying 70 flat against the back edges of said members on each side of the pivotal points to limit the movement of the members, substantially as described.

In testimony whereof we have hereunto set 75 our hands in the presence of two witnesses.

CARL MARSCHÜTZ.
HEINRICH MARSCHÜTZ.

Witnesses:

ANDREAS STENGEL,
OSCAR BOCK.
